UNITED STATES PATENT OFFICE.

JOHN B. CROFOOT, OF CHICAGO, ILLINOIS.

STAPLER.

Original application filed May 7, 1925, Serial No. 28,545. Divided and this application filed October 19, 1925. Serial No. 63,241.

My invention relates to a stapler, and has for an object to provide a stapler which has its body mounted on the base so as to be conveniently removed therefrom, and so arranged that the body may be used in conjunction with the base as a stapler and may also be removed from the base and separately used as a tacker; another object is to provide the stapler base with means for housing staples therein; and another object is to provide a stapler having a body which has elements reversibly mounted thereon so as to be used as stop means and to adapt said body for use with the base as a stapler, and also to have said elements reversed so as to act as protruding claws for engaging material and drawing and holding the same thereby adapting the body to be used as a tacker apart from the base. Other objects will appear hereinafter.

This is a division of applicant's prior application for patent for staplers, filed May 7, 1925, Serial No. 28,545.

The invention consists in the combinations and arrangements of parts hereinafter described and claimed.

The invention will be best understood by reference to the accompanying drawings forming a part of this specification, and in which,

Fig. 1 is an elevational view showing the present form of stapler body mounted in position on the base;

Fig. 2 is a vertical cross-sectional view, taken on line 2—2 of Fig. 1;

Fig. 3 is an elevational side view of the body with the stop plates reversed to adapt the body separately for use as a material puller and tacker;

Fig. 4 is an inverted plan view thereof, partly broken away; and

Fig. 5 is an elevational end view thereof.

The form of construction illustrated comprises a stapler body 30 removably mounted on a base 31 by means of a pair of lugs 32 on the base and a hand screw 33 having a knurled head 33' and passing through said lugs and through a guide member 34 adapted for guiding the staples 35 through the body member 30, to the front end 30' thereof, above the stapler block 36 on the base.

The base is provided with a chamber 37 in which a drawer 38 is removably mounted and adapted to receive a container or car-

tridge 39 adapted to contain and house the staples 35.

In this form of the invention the stapler body is particularly adapted for use as a tacker and to be useful in drawing material like screens for tacking them upon the frame bars and the like.

The stop means in this form include plates or members 41 which are adjustably mounted on each side of the body by the use of slots 42 on said plates engaging guide pins 43 on the body, each plate being firmly held in its adjusted position by a screw 44 engaging through a slot 45 on the plate. These slots are placed near one edge of the plate, so as to properly adapt the plates as stop means when mounted in the manner shown in Fig. 1, and also to make them properly adjustable on the body. These plates or members 41 are furthermore provided with claws or teeth 46 which are used to engage material such as a screen for drawing and holding the material in position on the screen bar or frame when said plates are mounted with the claws at the front end of the body, as shown in Fig. 3, and when the body is thus used as a tacker apart from the base. The screen or similar material may thus be engaged by the claws 46 and drawn in position on the frame bars, by the use of the body 30 arranged as indicated in Fig. 3, and by depressing the plunger in the usual manner the staple is driven in position through the screen or material into the frame.

It is apparent from the above disclosures that the body may be used with the base and employed as a stapler, and that said body may be used by itself with the plates arranged to have the claws at the front of the body, and to adapt the device as a tacker and that the device is especially adapted for use as a tacker and to draw the material into position upon a frame and to hold it in such position by the claws 46 during the tacking operation.

While I have illustrated and described the preferred form of construction for carrying my invention into effect, this is capable of variation and modification without departure from the spirit of the invention. I, therefore, do not wish to be limited to the precise details of construction set forth, but desire to avail myself of such variations and

modifications as come within the scope of the appended claims.

Having described my invention what I claim as new and desire to secure by Letters

5 Patent is:

1. A stapler comprising a base and a stapling body removably mounted thereon; a gauge plate mounted on one side of said body to project therefrom to overlap the 10 corresponding side of said base; and securing members arranged and adapted to secure said plate to said body in two positions, in one position said plate being secured in overlapping arrangement and in the other said 15 position said plate being secured in retracted position, substantially as described.

2. A stapler comprising a base and a stapling body removably mounted thereon; two gauge plates mounted on opposite sides of said body to overlap the sides of said base, said plates being provided with slots 20 adjacent the upper edges thereof; and securing members passing through said slots and adjustably securing said plates to said body, said slots and securing members being 25 arranged and positioned to permit of reversal of said plates on said body, thereby rendering said plates inoperative as gauge members, substantially as described.

In testimony whereof I have signed my 30 name to this specification.

JOHN B. CROFOOT.
